Primary Examiner — Steven J Czyz(74) Attorney, Agent, or Firm — Banner & Witcoff, Ltd.(57) CLAIM

The ornamental design for a storage rack with storage support, as shown and described.

DESCRIPTION

FIG. 1 is a top, front, left perspective view of a storage rack with storage support showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The uneven-length broken lines immediately adjacent to the shaded area represent boundaries of the claimed design and form no part thereof. The even-length broken lines depicting the remainder of the storage rack with storage support show portions that form no part of the claimed design.
